UNITED STATES PATENT OFFICE.

JOHN S. HOFFMIRE, OF AUBURN, NEW YORK.

CLOTHES TREE.

Application filed April 27, 1927. Serial No. 136,990.

This invention relates to certain improvements in clothes-trees; and the nature and objects of the invention will be readily recognized and understood by those skilled in the art in the light of the following explanations and detailed description of the accompanying drawings illustrating what I at present consider to be the preferred embodiments or mechanical expressions of my invention, from among various other forms, arrangements, combinations, and constructions of which the invention is capable within the spirit and the scope thereof.

In those types of clothes-trees or driers characterized by a vertical standard or mast having vertically spaced sets or series of radially disposed arms extending horizontally from the standard or column and pivotally mounted at the inner ends thereof for vertical swinging movement upwardly and inwardly to folded positions along and adjacent the standard or mast, the pivotal mounting and the desired retention or holding of the arms in their extended and in their inwardly folded positions, presents certain difficulties and problems from a mechanical, as well as from a manufacturing and assembly standpoint, in securing the required characteristics of low cost, mechanical simplicity with efficiency and durability in use. The present invention is directed to and holds as an object, a design, construction, and arrangement of mounting for such swingable clothes-tree arms on and from a standard or mast in which mechanical simplicity with efficiency in operation and use is secured, while retaining the desired characteristics of ready manufacture and assembly at low cost to permit of practical quantity production.

Another object of the invention is to provide a design and construction of mounting for a series of pivotally mounted radially disposed and vertically swingable clothes-tree arms, in which the arms are maintained under continuous yielding tension or pressure resisting swinging movements thereof and maintaining the arms in the desired positions to which swung.

Another object of the invention resides in providing a series of radially disposed arms for a clothes-tree or the like which are pivotally mounted at their inner ends for vertically swinging movements, with a series of expansion springs disposed under ten-

sion acting laterally upon the inner ends of the arms to resist swinging movement thereof and assist in maintaining the arms at the various positions to which they are swung.

Another object of the invention is to provide a supporting member or hub for mounting a series of clothes-tree or the like arms thereon extending radially therefrom, with the hub forming and providing supports for pivotally mounting and receiving the inner ends of the arms for swinging the arms vertically thereon to and from extended and vertically disposed or folded positions.

A further object of the invention is to provide a supporting member or hub for mounting a series of clothes-tree or the like arms thereon extending radially therefrom, with a series of spaced supports on and between which the inner ends of the arms are pivotally mounted for vertical swinging of the arms, and to further provide spring members between and yieldably exerting pressure laterally upon the inner ends of the arms to resist swinging thereof and assist in maintaining the arms in various positions to which they are swung.

A further object of the invention is to provide a supporting member for pivotally mounting a series of clothes-tree or the like arms thereon extending radially therefrom for vertical swinging movement of the arms thereon, with expansion spring assemblies carried by and on the pivots on which the inner ends of the arms are mounted yieldably exerting pressure laterally of the arms to resist swinging movements thereof.

A still further object of the invention is to provide a supporting member or hub for pivotally receiving and mounting a series of clothes-tree or the like arms thereon extending radially therefrom for vertical swinging movements, which member or hub is formed of two parts and readily assembled with the inner ends of the arms and their pivotal mounting assemblies, the entire design and construction being capable of low cost manufacture and assembly to form an efficient and durable arm unit in operation and use.

With the foregoing general objects, and certain other objects and results in view which will be readily appreciated from the following explanation, the invention consists in certain novel features in construction and

in combinations and arrangements of parts and elements as will be more fully and particularly referred to and specified herein-after.

5 Referring to the accompanying drawings, in which similar reference characters refer to corresponding parts throughout the several figures thereof.

Fig. 1 is a view in side elevation of a 10 clothes-tree or drier embodying the features of the invention, with the upper series or cluster of arms extended for use, and the lower series or clusters swung vertically to folded, inoperative position along and adjacent the standard or mast of the clothes-tree.

Fig. 2 is a view in top plan of a supporting member or hub unit and arms thereon in extended position swung outwardly therefrom and disposed radially therearound.

Fig. 3 is a horizontal section through the supporting member or hub unit of Fig. 2 with the arms in vertically disposed or folded position, and showing in top plan the mounting and arrangement of the pivot pins and spring assemblies for the arms in mounted position.

Fig. 4 is a bottom plan or interior view of the upper or cap member of the supporting member or hub unit, showing the arm slots and depending lugs or abutments for maintaining the spring assemblies and arm pivot pins in mounted assembled position.

Fig. 5 is a top plan view of the lower or base member of the arm supporting or hub unit, showing the spaced segmental standards therearound, on and between which the inner ends of the arms are pivotally mounted and supported.

Fig. 6 is a vertical transverse section taken on the line 6—6 of Fig. 2, through the arm supporting or hub unit with the arms in vertically disposed or folded position, and showing a manner of mounting and securing the unit to the clothes-tree or drier mast.

A clothes-tree or drier of the general type to which the invention hereof is particularly applicable is disclosed in Fig. 1 of the accompanying drawings, with the arm supporting and mounting units or hubs of the invention mounted thereon and incorporated therein, but it is to be understood that the various features of the invention are not limited or restricted to the disclosed embodiments thereof, or to use on and in connection with the type of clothes-tree or drier shown, as the invention may take other forms and is of general application and use to and on other types of devices for mounting a series or cluster of arms for swinging movements, wherever desired or found expedient, and the invention contemplates and includes such other forms and applications thereof.

65 In the example of an application and use

of the invention as shown in Fig. 1, a clothes-tree or drier is provided of the type embodying a base 10 supported upon the legs 11 having the rollers or casters 12 to permit of easily moving the clothes-tree to any desired location. A mast 14 is preferably, although not necessarily, rotatably mounted in and supported on a fitting or socket 15 carried by the base 10 centrally thereof, with the mast 14 disposed vertically and extending upwardly from the base, as will be clear by reference to Fig. 1. At vertically spaced intervals on and along mast 14, clusters or groups of arms or article supports 16 are mounted with the arms of each group spaced around the mast and pivotally mounted on horizontal axes for vertical swinging movement to positions horizontally and radially extended from the mast, as shown by the upper cluster or group of arms 16 in Fig. 1, or to folded positions inwardly to and vertically disposed along the mast 14, as shown by the lower clusters or groups of arms in Fig. 1. An arm supporting unit or hub 20 is provided for each group or cluster of the arms 16, which units or hubs are suitably mounted and fixed on the mast 14 at properly spaced points therealong to permit upward swinging of the arms 16 thereon to folded position. It is these arm supporting units or hubs 20 to which the present invention is particularly directed and relates.

These arm supporting units or hubs 20 in the example hereof are similar, and referring now to Figs. 2 to 6 inclusive, each comprises a base or lower plate member 21 of circular form having a central or axial bore or aperture 22 therethrough with a downwardly or outwardly extending collar 23 from the base surrounding such bore. The base member 21 is formed and provided with a series of spaced, vertically disposed segmental standards or supports 24 therearound, adjacent but spaced inwardly a distance from the outer or peripheral edge thereof, which standards 24 are, in the present instance, cast or otherwise formed integral with the base member. These segmental standards 24 are of substantially triangular form in cross-section, (see Figs. 3 and 5) with the bases thereof disposed at and forming the outer or front sides or walls of the standards, and substantially disposed in a circle passing therethrough concentric with the peripheral edge of the base 21, although not so limited. A series of arms 16 are mounted between the spaced standards 24 and extending radially and outwardly from the base 21 with the inner ends of the arms terminating spaced inwardly from the central bore 22 through the base, (see Fig. 2). The inner end of each arm 16 is mounted bearing and disposed laterally against a side wall 24a of an adjacent

standard 24, which standard side wall lies in a plane so disposed that with an arm 16 thereagainst, the longitudinal axis of the arm forms and lies along a radius of the base, as will be clear by reference to Figs. 2 and 3 of the drawings.

The arms 16 are pivotally mounted on horizontal axes disposed between the spaced standards 24 for vertical swinging movement of the arms to vertically disposed position extending upwardly from the base, as shown by Figs. 3 and 6, and this pivotal mounting of the inner ends of the arm 16 is accomplished in the example hereof by means of pivot pins 25 disposed transversely of the inner ends of the arms and extended laterally from opposite sides thereof across and supported at their opposite ends of the adjacent standards 24. The upper ends of the standards 24 are formed with the alined transversely disposed grooves 26 into which the ends of the pivot pins 25 of the arms 16 fit. Referring now to Figs. 3 and 5 in particular, it will be noted that each standard 24 is formed and carries two of the pivot pin receiving grooves 26 disposed at an angle to each other with one of these grooves alined with the corresponding groove of the standard at one side thereof, and the other of these grooves alined with the corresponding groove of the standard at the opposite side thereof. By this arrangement, each arm 16 is pivotally mounted and supported on and between the adjacent spaced standards 24 by means of a pivot pin 25 supported on and between these standards in the alined grooves 26 thereof, respectively, and is swingable vertically on the pivot pin to and from radially extended and upwardly disposed or folded positions. Due to the angular position of the pins 25 with respect to each other in grooves 26, with each pin end bearing against, or in proximity to the adjacent pin on a standard 24, the pins are locked or confined in position against longitudinal movement or displacement, as clearly shown by Fig. 3 of the drawings.

In order to maintain the arm 16 in position bearing against the faces or side walls 24^a of the adjacent standards 24, respectively, and in order to subject the arms to yieldable pressures acting laterally thereon for assisting in maintaining the arms in the positions to which swung, the invention provides spring assemblies mounted on and carried by the pivot pins 25. In the specific example hereof, these spring assemblies each comprise a coiled expansion spring 27 having suitable spring end containing centrally apertured plates or washers 28 at and on opposite ends thereof between which the spring extends. These spring assemblies so formed are mounted over and disposed on each arm pivot pin 25 between the side of the arm 16 opposite that engaging standard

wall 24^a and the wall 24^b of an adjacent standard, with the spring under compression or tension and exerting pressure laterally upon the arms to force the same against the standard side walls 24^a. It will here be noted that the standard walls 24^b are substantially parallel with the adjacent sides of the arms 16 respectively, so that the spring end containers 28 which bear against the spaced sides respectively, are substantially parallel with the springs maintained in approximately straight position therebetween. With the foregoing arrangement and mounting of the arms 16, they are continuously maintained under lateral pressure tending to resist swinging movements of the arms, while maintaining the arms in proper position against the standard side walls 24^a, by permitting free vertical swinging movements of these arms.

Each base 21 with the arms assembled and pivotally mounted and disposed thereon and therein as above described, is completed by an upper member or cap 30 to form the arm supporting units or hubs 20. These caps 30 are formed with a central or axial bore 31 therethrough of a diameter substantially equal to the diameter of the bore 22 of base 21 and with a side wall 32 extending therefrom and curving into the cap body. A cap 30 is fitted over and down onto a hub base 21 with the base fitting up into and received by the side wall 32, as is clearly shown by Fig. 6 of the drawings. The curved portion of the cap joining the side wall thereof fits over and across the upper ends of the arm mounting standards 24, closing the grooves therein and confining the arm pivot pins against displacement. A series of radial arm receiving slots 33 are formed through the cap 30 for receiving and through which the arms 16 swingably extend to permit of vertical movements thereof to and from extended and folded positions. Between the arm receiving slots 33 on the under or inner sides of the cap top wall, a series of depending lugs or abutments 34 are provided which in mounted assembled position of the cap on the base, lie over and above the springs 27 with pivot pins 25 to prevent upward displacement of the spring assemblies from proper mounted position with the pivot pins 25. Any suitable or desired bolts or the like 35 are provided for securing the cap 30 to the base 21, these bolts extending downwardly through the cap and the base as will be clear by reference to Fig. 6 of the drawings in particular.

The arm supporting units or hubs 20 with the arms 16 mounted and assembled thereon and maintained in position by the cap 30 bolted thereto, with the cap bore 31 in vertical alinement with the base bore 22, is mounted and secured in the desired position on the clothes-tree with the mast 14 extend-

ing through and received by the alined base and cap bores. A unit or hub 20 is fastened and secured in the desired position on mast 14 by means of screws or the like 36 extending transversely through the base collar 23 into and engaging the mast 14, as shown particularly by Figs. 1 and 6 of the drawings. Any desired number of the arm carrying and supporting units or hubs 20 can be mounted at spaced intervals on the mast 14 so as to leave sufficient space therebetween to permit of swinging the arms vertically upwardly to folded positions along and adjacent the mast, as will be readily understood. The clothes-tree or drier thus formed and constructed is capable of storage or location in restricted spaces by swinging all the arms thereof upwardly into folded position along and adjacent the tree mast, while these arms can be swung downwardly to horizontally disposed positions extending radially from the mast when it is desired to use the tree. If desired, the groups or clusters of the arms 16 can be arranged on the mast so that the arms of each group are staggered with respect to the arms of the groups thereabove and therebelow.

The design and construction of the arm supporting units or hubs 20, formed of the base 21 and the cap 30 is such that the arms and the spring assemblies can be quickly mounted and assembled therein and secured in assembled position by mounting a cap 30 therewith and thereon in the manner hereinbefore described. The formation of the base 21 of each unit or hub 20 permits of casting or otherwise forming this base with the arm supporting standards 24 integral therewith as a part thereof, to thereby eliminate the necessity of adding additional elements or parts thereto, as well as eliminating any finishing operations on these parts as cast with the base after removal thereof from the mold. Similarly, the cap members 30 of these units can be cast complete without the necessity of adding elements thereto or finishing the same before mounting on and assembly with the base. For the foregoing reasons and other obvious ones, the arm supporting units or hubs 20 are capable of low cost production and rapid assembly and mounting on and to a clothes-tree or drier mast or the like element.

Preferably, although not so limited, stops 29 are provided on the base 29 between the standards 24, at the outer edge of the base, and in line with the arms 16, so that the outer edges or sides of the inner ends of these arms engage the stops in folded, vertically disposed position of the arms, as will be clear from Fig. 5 of the drawings in connection with Fig. 6. The arms 16 are preferably cut away or notched on their outer edges or faces (not shown) to receive the stops in folded position and, thus insure

proper positioning of the arms in folded position, as will be readily understood.

In operation and use on a clothes-tree or drier of one of the arm units or hubs 20, the arms are maintained under continuous lateral pressure or tension by the springs 27 so that swinging movement of the arm on the pivot pins 25 is resisted and the arms in their vertically disposed folded positions are maintained against accidental displacement. The arms are upwardly swingable on the pivot pins 25 and the stops 29 on the base 21 are engaged by the inner ends thereof to limit upward or folding movements of the arms, while the downward extended movements of the arms are limited, and the arms are maintained in extended positions, by the undersurface of the cap 30 engaged thereby.

It is also evident that various other changes, variations, substitutions and modifications might be resorted to without departing from the spirit and the scope of my invention, and hence I do not wish to limit myself to the exact and specific disclosures hereof.

Desiring to protect my invention in the broadest manner legally possible, what I claim is:

1. In a clothes-tree arm supporting unit, a base, spaced standards therearound having their upper ends slotted, arms disposed with their inner ends between said standards, pivot pins disposed transversely of the arms between and supported in the slotted upper ends of the standards for pivotally mounting the arms on the base, and a cap member having a depending flange therearound secured over said base and having slots therethrough, said cap disposed over and closing the slotted upper ends of the standards and confining the pivot pins on the upper ends of the standards against displacement, the slots in said cap member being out of alinement with the slotted upper ends of the standards.

2. In a clothes-tree arm supporting unit, a base, a series of spaced standards thereon, pivot pins extending across and between said standards, arms mounted on said pins between the standards for swinging movement, spring assemblies mounted on said pins for exerting continuous pressure laterally on the arms, and a cap mounted on the base over said standards, the said cap being formed with slots through which the arms swingably extend, and members depending from said cap disposed over said spring assemblies, respectively, to prevent displacement of the assemblies and pivot pins on which said assemblies are mounted.

3. In a clothes-tree arm supporting unit, a base, a series of spaced standards disposed around the base extending upwardly therefrom, the upper ends of adjacent standards

- formed with alined grooves thereacross, a pivot pin disposed across adjacent standards and supported at its opposite ends in the alined grooves thereof, an arm swingably mounted on each of said pivot pins and extending from the base, an expansion spring for each arm mounted on each pivot pin under compression between the arm and an adjacent standard, and a cap mounted over the base, said cap being provided with depending portions confining said pins and springs against displacement, the said cap formed with radial slots for swingably receiving and through which said arms extend.
4. In a clothes-tree arm supporting unit, a base member, a series of spaced standards extending therefrom and disposed therearound, the upper ends of adjacent standards formed with alined grooves across the outer ends thereof, pivot pins disposed across and between adjacent standards supported at their opposite ends in the alined grooves thereof, respectively, a coiled expansion spring mounted on each pivot pin between the adjacent standards, an arm swingably mounted on each pin between an end of said spring and an adjacent standard with the spring under compression and continuously exerting lateral pressure on and forcing the arm against such standard, and a cap mounted over the base and formed with radial slots therethrough receiving and through which the pivotally mounted arms extend for swinging movement therein, said cap extending over and across the slots in the standards, and depending members on the cap positioned over said springs preventing displacement thereof with the pins.
5. In a clothes-tree arm supporting unit,
- a base, a series of upwardly extending standards disposed around the base, the upper ends of adjacent standards being formed with alined grooves thereacross, the grooves on each standard disposed at an angle to 45 and intersecting each other, pivot pins disposed across and between adjacent standards, respectively, supported at their opposite ends in the alined grooves thereof, an arm swingably mounted on each pivot between the standards and extending outwardly from the base, and each pivot confined between and against longitudinal displacement from its supporting grooves by the adjacent pins extending across the ends 55 thereof on the respective standards.
6. In a clothes-tree arm supporting unit, a base, a series of standards spaced around and extending from the base with their upper ends slotted, said standards formed with 60 grooves therein at the inner ends of the slots, arms disposed with their inner ends between adjacent standards, respectively, pivot pins disposed transversely of the arms between and supported in the grooves at the inner 65 ends of the slotted upper ends of the standards, spring assemblies on each pin between the arm thereon and an adjacent standard for exerting lateral pressure on the arm, a cap having a flange therearound mounted 70 on the base over said standard across the slotted upper ends thereof, and depending members on said cap disposed over said spring assemblies, respectively, to prevent displacement of the assemblies and pivot 75 pins.

Signed at Auburn, New York, this 14th day of April, 1927.

JOHN S. HOFFMIRE.
